Arthur G. Brown

ATTORNEY.

UNITED STATES PATENT OFFICE

HARRY BUTLER, OF KANSAS CITY, KANSAS

DESIGN FOR A BRACKET LIGHT OR SIMILAR ARTICLE

Application filed March 24, 1930. Serial No. 35,009. Term of patent 3½ years.

To all whom it may concern:

Be it known that I, HARRY BUTLER, a citizen of the United States, residing at Kansas City, in the county of Wyandotte and State of Kansas, have invented a new, original, and ornamental Design for Bracket Light or Similar Article, of which the following is a specification, reference being had to the accompanying drawings, forming part thereof.

Fig. 1 is a front elevational view of a bracket light or similar article, showing my new design.

Fig. 2 is a side elevational view of the same.

I claim:

The ornamental design for a bracket light or similar article, as shown.

HARRY BUTLER.
